UNITED STATES PATENT OFFICE.

WENDELIN P. SENG, OF CHICAGO, ILLINOIS.

CIRCUIT-CONTROLLING DEVICE.

1,134,355.

Specification of Letters Patent. Patented Apr. 6, 1915.

Application filed May 21, 1912. Serial No. 698,823.

To all whom it may concern:

Be it known that I, WENDELIN P. SENG, a citizen of the United States, residing at Chicago, in the county of Cook and State of Illinois, have invented a new and useful Improvement in Circuit-Controlling Devices, of which the following is a specification.

My invention relates particularly to circuit-controlling devices adapted for use in connection with motor-vehicles, and useful to control the electric circuits of electric horns, bells, or the like.

The primary object of my invention is to provide a device of the character indicated in which the circuit-controlling means is so disposed with relation to the steering-wheel of the vehicle as to enable the operator to sound the signal or horn without the necessity of removing his hands from the steering-wheel, and without the necessity of removing his feet from the brake and clutch pedals of the machine.

The invention is illustrated in its preferred embodiment in the accompanying drawings, in which—

Figure 1 represents a plan view of the steering-wheel of an automobile equipped with my improved circuit-controlling device; Fig. 2, a plan view of the annular contact-member employed, and its supporting spider; Fig. 3, a broken elevational view of the steering-wheel and shaft equipped with the improved device, the view being partly in section and illustrating also the electric horn and its circuit, the latter being shown diagrammatically; Fig. 4, a broken sectional view of a steering-wheel equipped with the device in modified form; Fig. 5, a broken sectional view showing another modification, the view being taken as indicated at line 5 of Fig. 6; Fig. 6, a broken sectional view taken as indicated at line 6 of Fig. 5; and Fig. 7, a broken sectional view showing a modification of the steering-wheel shaft.

Referring to the preferred construction shown in Figs. 1 to 3 inclusive, A represents the steering-wheel of an automobile mounted on a shaft A¹; B, an electric horn equipped with a vibrator B¹; and C, an electric circuit including a battery C¹.

In practice, the horn B is suitably mounted on any desired portion of the machine. On gasoline machines, the horn is commonly mounted under the engine hood in the vicinity of the lower end of the steering shaft. For convenience a diagrammatic

illustration is given in Fig. 3. One conductor 1 of the circuit C is grounded, that is, connected with a metal portion of the frame of the machine, so that the shaft A¹ forms a portion of the circuit. Upon the shaft is insulatingly mounted a collar 2, which carries resilient arms 3, upon which is mounted an annular contact-member 4. The other conductor 5 of the circuit C is connected to the collar 2. The annular contact-member 4 is disposed beneath the metallic arms 6 of the steering-wheel, and in close relation thereto; and said annular member is of somewhat smaller diameter than the steering-wheel, so that when it is desired, the operator may, without releasing his hold on the steering-wheel, employ his fingers to press the member 4 upwardly into contact with a rib, or ribs, of the steering-wheel, thereby closing the circuit C.

The collar 2 may consist of a two-part clamping-ring, as shown in Fig. 2. The clamping-ring is insulated by the bushing 7, which is of insulating material. Said clamping-ring, together with the spring arms 3, affords a spider which supports the ring 4. The ring 4 may comprise a rod bent into annular form and having its ends joined together by a union 8. The ring 4 lies in a plane parallel with the plane of the wheel A and immediately beneath the plane of the metal arms 6 of said wheel. The annular space 9 between the ring 4 and the rim 10 of the wheel is preferably of such width that the ring 4 will in nowise interfere with the manipulation of the steering-wheel, but the space 9 is nevertheless small enough to enable the operator to readily extend his fingers beneath the steering-wheel to press the member 4 upwardly to close the circuit. The conductor 5 extends downwardly along the shaft A¹, is suitably insulated, and may, if desired, be incased in a flexible metal armor. It is to be understood that the conductor 1 is shown connected with the shaft A¹ merely for convenience of illustration.

In the modification shown in Fig. 4, A₁ represents a portion of a steering-wheel, and 4_a represents in section an annular contact-member similar to the contact-member 4. In this modification, the annular contact-member 4_a is supported by extensible spring arms 3_a, which are carried by the rim of the wheel A₁. Any suitable number of extensible arms 3_a are employed. Each arm 3_a comprises an outer member 11 whose outer

extremity is secured to the rim of the wheel A₁, and whose inner end is telescopically received in a hollow or tubular member 12, which is secured to the annular member 4_a.
5 In this case, the conductor 5_a of the electric circuit is connected with the member 4_a; and the circuit is completed in the manner here-fores described.

In the modification shown in Figs. 5 and 10 6, 6_a represents an arm of a steering-wheel; and 4_b represents an annular contact-member similar to the contact-member 4. Here the annular contact-member 4_b is supported by a fiber sleeve 13, which is secured to the 15 arm 6_a of the steering-wheel. The sleeve 13 is provided with a slot 14, through which the annular member 4_b extends and is normally held depressed, or out of contact with the arm, by a spring 15. It will be understood, of course, that a supporting-sleeve 13 is employed at each arm of the steering-wheel. A conductor 5_b of the electric circuit connects with the annular contact-member 4_b. The contact is effected, as before, by 20 raising the annular member 4_b into contact with the arm of the steering-wheel.

In the illustration given in Fig. 7, A_a represents a steering-wheel shaft which is encircled by a fixed tube or sleeve 16. In an 25 automobile having such a fixed sleeve inclosing the steering-wheel shaft, the collar 2 would be secured upon the upper end of the fixed tube. In such case, the steering-wheel would turn with relation to the annular contact member 4, but this would in nowise interfere with the operation of the device. In the construction shown in Figs. 1 and 3, the collar 2, being fixed to the steering-wheel shaft, which turns, no relative rotation be-

tween the steering-wheel and the annular contact-member occurs.

From the foregoing description, it is evident that my device possesses many advantages, can be manufactured at a moderate cost, and can readily be applied to both old and new automobiles. The detailed description has been given for clearness of understanding; hence no undue limitation should be understood therefrom, but the appended claims should be construed as broadly as 40 permissible in view of the prior art.

What I regard as new, and desire to secure by Letters Patent, is:

1. The combination with a steering-wheel and its shaft, of an electric circuit comprising a collar encircling the steering-wheel shaft and insulatingly mounted thereon, arms supported by said collar, and an annular contact-member supported by said arms and disposed close to the steering-wheel.

2. The combination with a steering-wheel and its shaft, of an insulatingly-mounted collar encircling said shaft, resilient arms carried by said collar, and an annular contact-member carried by said arms and disposed close to the steering-wheel.

3. In means of the character set forth adapted to be mounted on the steering-shaft of an automobile, the combination of a collar, means for insulatingly mounting the same on said steering-shaft, and a spring-carried annular contact-member mounted on said collar.

WENDELIN P. SENG.
